(57) **CLAIM**

The ornamental design for an electrical junction box, as shown and described.

DESCRIPTION

FIG. 1 is a perspective front side view of a first embodiment of the electrical junction box;

FIG. 2 is a front elevational view of the design shown in FIG. 1;

FIG. 3 is a right side elevational view of the design shown in FIG. 1;

FIG. 4 is a rear elevational view of the design shown in FIG. 1;

FIG. 5 is a left side elevational view of the design shown in FIG. 1;

FIG. 6 is a top elevational view of the design shown in FIG. 1;

FIG. 7 is a bottom elevational view of the design shown in FIG. 1;

FIG. 8 is a perspective front view of a second embodiment of the electrical junction box;

FIG. 9 is a front elevational view of the design shown in FIG. 8;

FIG. 10 is a right side elevational view of the design shown in FIG. 8;

FIG. 11 is rear elevational view of the design shown in FIG. 8;

FIG. 12 is a left side elevational view of the design shown in FIG. 8;

FIG. 13 is a top perspective view of the design shown in FIG. 8; and,

FIG. 14 is a bottom perspective view of the design shown in FIG. 8.

In the drawings, the broken lines are for the purpose of illustrating environment only and form no part of the claimed design.
